UNITED STATES PATENT OFFICE.

JOHN H. LAWRENCE, OF STERLING, ILLINOIS.

TRACK FOR BARN-DOOR HANGERS.

SPECIFICATION forming part of Letters Patent No. 350,538, dated October 12, 1886.

Application filed June 16, 1886. Serial No. 205,371. (No model.)

To all whom it may concern:

Be it known that I, JOHN H. LAWRENCE, a citizen of the United States, residing at Sterling, in the county of Whiteside and State of Illinois, have invented certain new and useful Improvements in Tracks for Barn-Door Hangers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to tracks for barn-door hangers, and pertains more especially to the form of the track.

The object of my invention is to secure the strongest possible track and one which will 20 neither sag vertically, nor warp horizontally, nor twist.

In connection with the track I exhibit a novel brace or bracket for attaching such track to the barn, though other forms of bracket 25 might be easily substituted.

The advantage I claim for my track is not alone that its form secures the maximum of inherent strength in proportion to the quantity of the material employed, but that such 30 form also renders the tracks susceptible of the most strong and permanent attachment to the building.

As my track is adapted to be used with any of the double-tread rollers, and my invention 35 pertains only to the track and its attachment, I do not deem it necessary to show or describe the roller further than to show its location.

Figure 1 is a cross section of a track exhibiting my invention. Fig. 2 is a perspective 40 of the bracket. Fig. 3 exhibits the mode of attaching the track and bracket and the position of the supported roller thereon.

A is the track, which, to obtain the utmost of strength and durability, I make of rolled 45 steel, and therefore of one solid or integral piece. It will be noticed that the cross-section of the track A is in the form of a cross or four equidistant longitudinal ribs, B, C, D, and E. The outer lateral rib, B, and inner lateral 50 rib, C, constitute the track of the carrying-rollers, the latter being attached to the door in any of the usual modes.

The track A is intended to support and be traversed by a roller having two wheels or a double tread, and such wheels will have their 5 tread respectively on the ribs B and C, as shown in Fig. 3. The upper rib, D, projects upward between the wheels of the roller F and serves to guide such rollers and keep them on the tracks. The lower rib, E, furnishes a convenient part to which to attach the outer end of the bracket G. The bracket G is formed of a steel plate bent to form two right angles and two straight ends parallel with each other, and one straight side. The inner end, H, of 65 the bracket G is long enough to furnish suitable screw-seats, a a, for attachment to the building. The side J of the bracket G is of sufficient breadth to allow the door, when hung, to swing clear of the barn. The upper portion 70 of the side J slopes diagonally downward toward the outer end, K, of such bracket, so as to be out of the way of the roller, and yet furnish a brace-support for the track A. The outer end, K, of the bracket G equals in height 75 the lower rib, E, of the track A, and is placed against and parallel with such rib E and attached thereto by the transverse bolt or rivet M, passed through the end K and rib E. The upper edge of the end K and so much of the 80 side J as extends under the said lateral rib C are of uniform height and abut against the under side of the last-named rib and afford additional support thereto.

It is obvious that the ribs D and E give the 85 track A great strength in a vertical plane, and the lateral ribs, B and C, in like manner afford great strength to said track against outward or inward pressure.

The bracket G can be placed at any desired 90 intervals along the track A—about one foot apart will be found satisfactory.

It is not essential that the under sides of the ribs B C shall be horizontal laterally, nor that the rib E shall have perpendicular sides, 95 only that the outer end of the bracket G be seated firmly against the ribs C and E.

What I claim as my invention, and desire to secure by Letters Patent of the United States, is—

In a barn-door track, the combination of the integral bracket G set edgewise and having its side J lower at its outer extremity so as to permit the passage of the door, and having its

ends H and K bent at right angles with its central portion to form seats for attachment to the rail and building, respectively, and the track A, formed of four integral equidistant longitudinal ribs, B, C, D, and E, the outer end, K, of the bracket G being projected under the rib C and suitably attached to the rib E, whereby the outer end of said bracket can be projected between the door and its supporting-

roller, and said bracket be in position to exert to its greatest strength, substantially as shown, and for the purpose described.

In testimony whereof I affix my signature in presence of two witnesses.

JOHN H. LAWRENCE.
